his Attorney

UNITED STATES PATENT OFFICE.

OSCAR A. BETTUM, OF WASHINGTON, DISTRICT OF COLUMBIA.

WATCHMAKER'S HAND VISE.

Application filed February 28, 1927. Serial No. 171,661.

This invention is in the nature of a hand vise for holding small articles to permit a workman to make repairs thereon, and is particularly designed for use as a watchmaker's work holder.

It is an important object of the present invention to enable the convenient and efficient manipulation of the tool by one hand to open and close the movable jaw of the vise, and thereby leave the other hand free for placing the work piece upon the tool and removing the same therefrom.

A further object of the invention is to enable the convenient assemblage and separation of the parts of the tool so as to enable the ready repair of the tool in the event of wear or breakage of any of its parts.

With these and other objects in view, the present invention consists in the combination and arrangement of parts as will be hereinafter more fully described, illustrated in the accompanying drawings and particularly pointed out in the appended claims, it of course being understood that changes in the form, proportion, size and minor details may be made, within the scope of the claims, without departing from the spirit or sacrificing any of the advantages of the invention.

In the drawings:

Figure 1 is a longitudinal sectional view of a watchmaker's tool embodying the features of the present invention;

Figure 2 is an enlarged detail sectional view;

Figure 3 is a view similar to Figure 2 and showing a balance wheel held by the tool;

Figure 4 is a detail perspective view of the movable jaw element of the tool;

Figure 5 is a side elevation showing the tool propped upon a work table with a work piece held by the tool;

Figure 6 is a detail elevation of the detachable propping member.

Figure 7 is a view similar to Figure 2 with the jaws separated and their co-acting faces disposed oblique to the longitudinal axis of the tool.

The present tool includes a tubular open ended casing 1, which may be externally tapered at its front end as at 2. The tapered portion is externally smooth, while the cylindrical portion of the casing is knurled, as best shown in Figure 5 of the drawing.

Mounted for endwise reciprocation with-

in the casing is a plunger made up of a tubular shank 3, and a stem 4, the shank and stem having a screw-threaded detachable connection 5. The forward end of the shank 3 projects at the front end of the casing, while the rear end of the stem 4 projects at the rear end of the casing and is provided with an enlarged head 6 outside of the casing. The projecting end of the shank is tapered and cut away or notched, at 7, so as to form an abutment, shoulder or jaw 8, and the shank is preferably solid from the jaw 8 to the forward end of shank. Within the shank is a rod 9 having an elbow or lateral extension 10 at its rear end which is received through a slot 11 in the rear end of the tubular shank 3, with the outer extremity of the projection received in a hole or recess 12 provided in the casing whereby the rod 9 is anchored or held against independent longitudinal movement within the casing. The rod 9 is of a length to have its forward end normally engage the jaw 8 of the shank 3, and said forward end of the rod constitutes the fixed jaw of the vise.

The jaws are normally and yieldably held in mutual engagement by means of a helical spring 13 lying within the casing and embracing the reduced portion 14 of the stem, said reduced stem portion providing a shoulder or abutment 15 against which the rear end of the spring engages. A bushing 16 embraces the slotted rear end of the shank 3 and engages at one end the elbow or projection 10 as a stop, while its opposite end constitutes an abutment or shoulder for engagement by the forward end of the spring. The spring is an expansion spring normally operating to hold the shank and stem retracted with the movable and fixed jaws in engagement and the head 6 spaced in rear of the casing. The bushing is employed to give a more substantial bearing for the forward end of the spring.

In using the present tool, the casing is held between the first and second fingers of one hand, and the thumb, of the same hand, is pressed against the head 6 to thrust the plunger forward and separate the jaws of the device after which the work piece, as for instance a balance wheel 17, is taken in the other hand and placed between the jaws, and then the pressure of the thumb on the head 6 is released and the spring is permit-

ted to move the plunger rearwardly thereby to grip the work piece between the jaws, as shown in Figure 3 of the drawings. By 5 separating and the work piece released. The jaws are clamped upon the work piece by the action of the spring leaving the hand free to hold the tool in any desired position.

For supporting the tool in the manner 10 shown in Figure 5, a prop member 18 may be employed. This prop member is in the form of a plate having a hole or opening 19 to receive the tapered forward end 15 of the plunger, and has a straight bottom edge to rest upon a table, work-bench or other support, with the rear end of the tool also resting upon the same support, thereby to rigidly support the work piece in position to enable the repair man to work upon 20 the article to be repaired. Of course, the prop 18 is removable in order that the tool may be employed under conditions where the prop might interfere, and it will be understood that the prop is not essential to the 25 holding function of the tool. The tapered shape of the forward end of the plunger enables the wedging thereof within the opening 19 of the prop so as to obtain a simple and effective rigid connection between the 30 prop and the tool, while the prop may be conveniently removed without disturbing any parts of the tool or requiring loosening or removal of any fastenings.

The tool may be employed in a vertical 35 position with the forward end of the shank 3 resting upon a table, work bench or other support.

In some instances it may be desirable to 40 have the work piece disposed obliquely with respect to the longitudinal axis of the tool, and to provide for this disposition of the work piece, see Figure 7, the movable jaw 8 and the fixed jaw formed by the forward 45 end of the rod 9 are disposed in parallelism obliquely with respect to the longitudinal axis of the tool and inclined forwardly and outwardly.

What I claim is:

1. A tool comprising an open ended tubular casing, a plunger working in the casing and projecting at opposite ends thereof, a spring forcing the plunger rearwardly, the forward portion of the plunger being tubular and having a notch therein and also provided with a slot, and a rod lying in the tubular portion of the plunger and having a lateral projection extending through the slot in the plunger and anchored to the casing, the front end of the rod and the front 55 wall of the notch in the plunger cooperating as vise jaws.

2. A tool comprising an open ended tubular casing, a plunger working in the casing and projecting at opposite ends thereof, the forward portion of the plunger consist-

ing of tubular shank, the rear portion of the plunger consisting of a stem detachably connected to the shank and provided with a reduced portion forming a shoulder, a helical spring embracing the reduced portion 70 of the stem and bearing at one end against the shoulder on the stem, the opposite end of the spring being fixed, the tubular shank having a notch therein in front of the casing, and a rod lying in the tubular shank and 75 fixed to the casing, the front wall of the notch and the front end of the rod constituting co-acting vise jaws.

3. A tool comprising an open ended tubular casing, the rear portion of the bore 80 of the casing being enlarged and providing an internal annular shoulder, a tubular shank working endwise in the casing and having a working fit within the forward portion thereof, the front portion of the 85 shank projecting beyond the casing and provided with a transverse notch, the rear portion of the shank having a longitudinal slot and also internally screw-threaded, a rod lying within the tubular shank and having a transverse projection extending through the slot of the shank and secured to the casing, the front wall of the notch and the front end of the rod constituting co-acting 90 vise jaws, a bushing embracing the inner end 95 of the shank and lying against the rear side of the lateral projection on the rod, a stem working within the casing and projecting at the rear end thereof, the forward portion 100 of the stem being reduced to form an annular shoulder and also screw-threaded and detachably engaged with the screw-threads on the tubular shank, and a helical spring embracing the reduced portion of the stem and bearing at one end against the shoulder on 105 the stem and at its opposite end against the bushing.

4. A tool of the character described comprising a tubular casing, a plunger working in the casing and projecting at opposite ends 110 thereof, a spring forcing the plunger rearwardly, the forward portion of the plunger being tubular and having a notch therein and also provided with a longitudinal slot, and a rod lying in the tubular portion of 115 the plunger and having a lateral projection extending through the slot in the plunger and anchored to the casing, the front end of the rod and the front wall of the notch in the plunger being disposed obliquely with 120 respect to the longitudinal axis of the plunger and cooperating as vise jaws.

5. A tool comprising an open ended tubular casing, a plunger working in the casing and projecting at opposite ends thereof, a spring forcing the plunger rearwardly, the forward portion of the plunger being tubular and having a notch therein and also provided with a slot, and a rod lying in the 125 tubular portion of the plunger and anchored 130

against endwise movement, the front portion of the rod and the front wall of the notch in the plunger cooperating as vise jaws.

6. A tool comprising an open ended tubular casing, a plunger working in the casing and projecting at opposite ends thereof, a spring forcing the plunger rearwardly, the forward portion of the plunger being tubular and having a notch therein and also pro-

vided with a slot, and a rod lying in the tubular portion of the plunger and having a lateral projection extending through the slot in the plunger and anchored to prevent endwise movement of the rod, the front end of the rod and the front wall of the notch 15 in the plunger cooperating as vise jaws.

OSCAR A. BETTUM.
